PACKAGE

William Glidden Freel, London, Ontario, Canada,
assignor, by mesne assignments, to Canadian
Nasal Spray Company Limited, Toronto, Ontario, Canada

Application July 5, 1940, Serial No. 344,159

2 Claims. (Cl. 206—80)

My invention relates to packages of the combined stock and display type. In more specific terms it pertains to a means of securing an article for display in a carton. In packages of this type articles displayed are usually set in openings in a false bottom, the openings conforming more or less with the contour of the articles whereby they are retained by friction. It so happens, however, that such articles which are of spherical or nearly spherical shape and of greater dimensions than the average of the articles in the package are not adapted to be held by the common false bottom due to the fact that articles of this shape do not present any surface perpendicular to the adjacent opening in the bottom.

In ordinary practice such articles are usually held by means of wires or cords passing around the articles and having ends tied together under the bottom. This is found unsatisfactory for obvious reasons among which are the time required and difficulty in fastening the same, the impossibility of removing the goods for examination, and difficulty in removing the goods with consequent damage to the goods as well as to the package.

The above drawbacks are obviated by the new means of fastening which I have conceived and which consist of a flat band, preferably of similar material as that of the carton, adapted to partly encircle the article or part of the article to be held, and having ends so formed that they will engage underneath the edge around the adjacent opening in the bottom. The band may be removed without damage to the goods nor to the carton and may be replaced if desired without difficulty. It is quickly applied, economical to produce and will not mar the goods thereby held.

The objects of my invention are therefore:

To provide a means of fastening goods in a display which is quickly applied and without the aid of any tool;

To provide a means of fastening goods in a display which does not mar the goods and which allows their removal without damage to the package;

To provide a means of fastening goods in a display which is generally practical and economical.

Other objects as well as advantages of the invention will become apparent by perusal of the following description of one application thereof shown in the drawing appended thereto and in which:

Figure 1 is a plan view of a carton, cover removed, showing a medical atomizer and a supply component displayed therein;

Figure 2 is a plan view of the false bottom carton blank;

Figure 3 is a plan view of the holding band in accordance with my invention;

5 Figure 4 is a sectional view of the atomizer compressible tube and portion of the carton taken on line 4—4 of Figure 1 showing the band in position, and

Figure 5 is an underside view of that portion 10 of the false bottom adjacent the compressible tube location showing the band in position.

Similar reference numerals denote identical parts or portions thereof in all the figures.

In the present instance it will be seen that the 15 supply component in the form of a stoppered bottle 10 is easily held in place by being inserted in opening 11 stamped out of false bottom 12. It is also evident that the adapter cap 13 of the atomizer component may be easily held to the 20 false bottom by inserting the same in opening 14 and inserting tongue 15 therein. However, while there is an opening 16 to allow compressible tube 17 of the atomizer component to sink down to an extent equal to the space between the 25 false bottom and the normal bottom 18 of the carton it cannot hold itself against upward movement. One reason in this particular case is due to the fact that the false bottom is spaced from the main bottom by means of its integral downward walls 19 which have a height suitable to 30 reach at least halfway along the sides of the bottle but only to a point below the axis of tube 17.

By holding the tube downwardly in opening 16 35 it will become fixed against vertical as well as side motion. This is accomplished by means of a retainer 20 of strap-like form and of substantially I-shaped contour. The retainer 20 includes an intermediate part of the desired width and length and a pair of end parts 21 of like form of greater width than and extended laterally in opposite directions with respect to the ends of the aforesaid intermediate part. The end parts are of segmental shape and oppositely disposed. The end parts 21 constitute bendable holders and are oppositely disposed. Each end part includes a continuous outer edge 22 of arcuate form and a pair of spaced straight aligned inner edge portions 23 disposed in lateral relation with respect to the side edges of the intermediate part of the retainer 20. The length of the retainer is such that when tightly surrounding the tube and its ends allowed to extend in the opening thereunder, the straight inner edge portions 23 of ends 21 will be just below the

lower face of the false bottom. Owing to the fact that opening 16 is of curved contour and that the ends 21 of the band are flat, straight edge portions 23 will lie under the false bottom surface as shown in Figure 5 as at A.

In the application, the retainer is bent U shape so as to straddle the article to be held and the ends are forced tangentially through and along the opposite edges of the opening thereunder. In so doing, the resiliency of the band material will allow the end parts 21 to curve in agreement with the curve of the opening and also allow the same to straighten out as soon as edge portions 23 reach below the surface of the false bottom locking the band thereunder. The rounded edge 22 of each of the end parts 21 permits easy insertion in the opening. If desired the locking effect may be enhanced by bending the outer portion of end parts 21 (as shown at B Figure 5) so as to cause them to reach further under the false bottom. When the article is fastened to the false bottom before the latter is placed in the carton, this bending may be effected after the insertion of the band. Alternately when the article to be held is mounted after the false bottom is already in place the bending of portions 23 is done beforehand by creasing along a line shown in dots at 24.

If it is desired to remove the article from the display position without tearing the retainer, it may be done by compressing the band and tube between the fingers to a size narrower than the width of the opening thereby withdrawing the ends of the band from underneath the bottom.

5 I claim:

1. In combination with a display carton having a false bottom therein and article locating opening in said bottom, means for holding said article in relation with said opening comprising a retainer of strap-like form and of flexible material adapted to straddle said article, said retainer having an intermediate part and a pair of oppositely disposed end parts extending laterally in opposite directions with respect to the ends of the sides of said intermediate part, said end parts having inner edge portions adapted to underlie the edge of said opening when said end parts are passed through said opening.

10 2. The invention as set forth by claim 1, having said end parts each in the form of a segment of a circle provided with a continuous outer edge of arcuate contour and spaced inner endwise aligned oppositely extending straight inner edge portions disposed in lateral relation with respect to said intermediate part.

15 WILLIAM G. FREEL.
